[57] CLAIM

The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of a second embodiment of the design of FIG. 1, the only difference being in the height; and,

FIG. 6 is a side elevational view of a third embodiment of the design of FIG. 1, the only difference being in the height. The flower pot cover has no substantial thickness.
